J. W. Bowers,
Inventor.

331st Cadmore & Co. Attorney

UNITED STATES PATENT OFFICE.

JAMES W. BOWERS, OF PEARLINGTON, MISSISSIPPI, ASSIGNOR OF ONE-HALF TO
WILLIAM D. McCURDY, OF TORONTO, OHIO.

GATE LATCH.

Application filed August 18, 1921. Serial No. 493,390.

To all whom it may concern:

Be it known that I, JAMES W. BOWERS, a citizen of the United States, residing at Pearlington, in the county of Hancock and State of Mississippi, have invented a new and useful Gate Latch, of which the following is a specification.

This invention relates to latches especially designed for use in connection with fence gates although it is to be understood that it can be employed wherever desired.

It is an object of the invention to provide a latch having an actuating spring for holding the latch normally projected, means being provided for housing this spring so as to protect it from the elements.

Another object is to provide a novel means for holding the bolt of the latch in projected or locking position so that it cannot be withdrawn from its keeper until after a suitable key has been used.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is an elevation of the latch applied to a gate a portion of which has been shown.

Figure 2 is a plan view of the latch, the gate being shown in section.

Figure 3 is an enlarged section on line 3—3, Figure 1.

Figure 4 is a section on line 4—4, Figure 3.

Figure 5 is a section on line 5—5, Figure 1.

Figure 6 is a section on line 6—6, Figure 1.

Figure 7 is a plan view of a modified form of keeper.

Referring to the figures by characters of reference 1 designates an attaching bracket having an opening 2 extending therethrough and another attaching bracket 3 is provided and is adapted to be placed parallel with

the bracket 1, both of these brackets being 55 attached in any suitable manner to the gate G. An opening 4 is extended through the bracket 3 and in line with the opening 2 and secured to one side of the bracket 3 is a tubular housing 5 which can be braced in 60 any suitable manner, as by means of a bracket 6 of any suitable construction engaging the housing 5 and attached to the gate. Slidably mounted within the openings 2 and 4 is a bolt 7 one end of which 65 extends into the housing 5. To this end of the bolt is secured one end of a coiled spring 8 the other end of which is attached to the bracket 3 so that the bolt is held normally projected through the bracket 1 as shown 70 for example in Figure 2.

A disk 9 is secured to one face of the bracket 3 and has an opening 10 extending therethrough and registering with a corresponding opening 11 in the bracket 3. A 75 collar 12 is secured to the bolt 7 and has a pin 13 extending therefrom parallel with the bolt, this pin being slidable within the openings 10 and 11 so as to hold the bolt 80 against rotation.

Secured to one side of the bracket 1 is a substantially circular housing 14 in which is secured a stem 15 mounted for rotation and having an angular head 16, this stem preferably projecting entirely through the 85 bracket 1 as shown in Figure 4. Secured to this stem so as to rotate therewith is a locking disk 17 the marginal portion of which is adapted to extend into a groove 18 formed in the bolt 7, thus to hold the 90 bolt against longitudinal movement after it has been projected into engagement with its keeper. A peripheral recess 19 is provided in the disk 17, however, so that by placing a suitable key 20 in engagement with the 95 head 15 and rotating disk 17 this recess can be brought opposite the groove 18 so as to allow the bolt to be shifted longitudinally.

A collar 21 is secured to the bolt 7 and is adapted to come against the housing 14 so 100 as to limit the sliding movement of the bolt 7 in one direction.

A grip 22 is secured to the bolt between the collars 21 and 12 and constitutes means whereby the bolt can be easily grasped and 105 shifted.

For the purpose of fastening the bolt in retracted position an opening 23 is extended

through that portion of the bolt within the bracket 1. This opening is adapted to register with a hole 24 formed in the bracket 1 so that when the bolt is retracted a holding pin 25 can be inserted into the hole 24 and the opening 23 as shown in Figure 5. The hole 24 can be countersunk as shown at 26 to receive the head 27 of the pin 25 and a cover plate 28 can be pivotally connected 10 to the bracket 1 so as to conceal the hole 24 and fasten the pin 25 in place.

Any desired form of keeper can be used in connection with the bolt. For example, and as shown in Figure 2, the gate post P 15 can be mortised as shown at 29 to receive an obliquely disposed strike plate 30. This plate can be provided with an opening 31 sufficiently large to receive the bolt and which opening registers with a recess 32 in 20 the post. Thus when the gate is closed the yieldingly held bolt projecting beyond the end of the gate will come against the strike plate 30 and ride therealong until it comes opposite the opening 31 whereupon it will 25 enter said opening and the recess 32.

If a round post such as one formed of pipe is used, as shown at P' in Figure 7, the keeper can be formed of two clamp members 33 and 34 held together by screws 30 or bolts 35 adapted to be clamped upon the post. The strike plate 36 can be made a part of or can be attached to the member 34

and supported at the proper angle as shown in Figure 7.

When it is desired to lock the bolt against 35 retraction from its keeper it is merely necessary to rotate the disk 17 by means of its key so as to move the recess 19 away from the bolt 7 and cause the marginal portion of the disk to enter the groove or slot 18. 40

What is claimed is:—

The combination with spaced brackets, of a bolt slidably mounted therein, resilient means for holding the bolt normally projected beyond one of the brackets, a grip 45 upon the bolt and between the brackets, said bolt having a notch therein, a locking disk mounted for rotation on one of the brackets, said disk being rotatable into the notch to hold the bolt retracted, there being a notch 50 in the disk for receiving the bolt to release the bolt under the action of its spring, key operated means for rotating the disk, and cooperating means upon the bolt and one of the brackets for holding the bolt against 55 rotation.

In testimony that I claim the foregoing as my own, I have hereto affixed my signature in the presence of two witnesses.

JAMES W. BOWERS.
